UNITED STATES PATENT OFFICE.

BENJAMIN J. GREER, OF POYNOR, TEXAS.

WRENCH.

Application filed April 3, 1922. Serial No. 549,032.

To all whom it may concern:

Be it known that I, BENJAMIN J. GREER, a citizen of the United States, residing at Poynor, in the county of Henderson and State of Texas, have invented certain new and useful Improvements in Wrenches, of which the following is a full, clear, and exact description.

My invention relates to wrenches, and has for its object to provide a simple construction whereby the wrench may be quickly adjusted for varying sizes of pipe or the like, and after being so adjusted the jaws of the wrench may be firmly clamped to the pipe by a lever action having a shiftable fulcrum.

Other objects and advantages of the invention will be apparent from the following description when taken in connection with the accompanying drawing, in which:

Figure 1 is a side elevation of the wrench, showing in dotted lines the clamped position of the elements.

Figure 2 is an edge view of the wrench.

Figure 3 is a fragmentary sectional view, and

Figure 4 is a horizontal section through the wrench.

Referring to the drawing more in detail, the numeral 1 designates the arm of the wrench provided with a handle 2. Fixed to the upper end of the arm 1 is a jaw 3, which has extending laterally therefrom a loop 4. Slidably mounted in the loop 4 by means of shank 5 is a second or movable jaw 6.

A lever 7 is pivoted to the lower end of shank 5, as indicated at 8, and this lever in turn has pivoted thereto a link 9, as indicated at 10. The lever 7 is beveled at its lower end to provide a screw driver as shown in Figure 1.

Formed on an edge of the arm 1 are a plurality of ratchet teeth 11, and partly encircling this arm and adapted to engage the ratchet teeth is a U-shaped member 12. The free ends of the U-shaped member 12 are connected by means of a pin or the like 13.

In operation of the device the lever 7 of the wrench is drawn down until the jaws 3 and 6 engage the pipe 14 or other object to be operated upon. The U-shaped member 12 is then adjusted along the ratchet teeth 11 until the pin or abutment 13 engages the free end of the link 9, the lever 7 being held in the position shown in full lines in Figures 1 and 2. If the lever 7 is now moved

on its pivot toward the handle 2 it will be seen that the jaw 6 will be drawn toward the jaw 3 and firmly grip the object therebetween. This action is due to the fact that the link 9 abuts the pin 13 and in combination with lever 7 forms a toggle for drawing the jaw 6 downwardly. The free end of link 9 may have a slight lateral movement relative to the pin 13, but it cannot move longitudinally of the wrench except when the U-shaped member 12 is adjusted along the rack 11.

The ratchet teeth 11, U-shaped member 12 with its abutment 13, and the link 9 together form a shiftable fulcrum for the lever 7 whereby the wrench may be adjusted to practically any size of pipe and yet have a fulcrum which will provide sufficient leverage for firmly gripping the same.

In accordance with the patent statutes, I have described what I now believe to be the best embodiment of the invention, but I do not wish to be understood thereby as limiting myself or the scope of the invention, as many changes and modifications may be made without departing from the spirit of the invention; all such I aim to include in the scope of the appended claims.

What I claim as new and desire to secure by Letters Patent is:

1. A wrench including an arm, a jaw fixed with respect thereto, a second jaw movably mounted with respect to the fixed jaw, a lever pivoted to the movable jaw, an abutment adjustably mounted on the arm, and a pivoted link on the lever for engaging said abutment.

2. A wrench including an arm having ratchet teeth formed thereon, a jaw fixed to said arm, a second jaw movably mounted with respect to the fixed jaw, a lever pivoted to the movable jaw, a U-shaped member encircling a portion of the arm and adapted to engage said ratchet teeth at the base of the U, an abutment connecting the free ends of the legs of the U-shaped member, and means on said lever for engaging the abutment.

3. A wrench including an arm having ratchet teeth formed thereon, a jaw fixed to said arm, a second jaw movably mounted with respect to the fixed jaw, a lever pivoted to the movable jaw, a U-shaped member encircling a portion of the arm and adapted to engage said ratchet teeth, an abutment connecting the free ends of the

legs of the U-shaped member, and a link on said lever for engaging the abutment.

4. A wrench including an arm having ratchet teeth formed thereon, a jaw fixed to said arm, a loop connected to said arm, a second jaw slidably mounted in the loop, a lever pivoted to the sliding jaw, a U-shaped member encircling a portion of the arm and adapted to engage said ratchet teeth at the base of the U, an abutment on said U-shaped member, and means on said lever for engaging said abutment.

5. A wrench including an arm, a jaw fixed with respect thereto, a second jaw movably mounted with respect to the fixed jaw, a downwardly extending shank on the movable jaw, a lever pivoted to said shank, an abutment adjustably mounted on said arm and interposed between the arm and shank, and a link pivoted to said lever and adapted to engage said abutment.

6. A wrench including an arm, a jaw fixed with respect thereto, a jaw movably mounted with respect to the fixed jaw, a

downwardly extending shank on the movable jaw, a lever pivoted to said shank, an abutment adjustably mounted on said arm and interposed between the arm and shank, and an L-shaped link pivoted to said lever and adapted to engage said abutment.

7. A wrench including an arm having ratchet teeth formed thereon, a jaw fixed to said arm, a second jaw movably mounted with respect to said fixed jaw, a downwardly extending shank on the movable jaw, said shank extending substantially parallel to said arm and on the side thereof remote from the ratchet teeth, a straight lever pivoted to the shank and extending downwardly therefrom on the same side of the arm, a U-shaped member encircling a portion of the arm and adapted to engage said ratchet teeth, an abutment connecting the free ends of the legs of the U-shaped member and interposed between the shank and arm, and means on the lever for engaging said abutment.

BENJAMIN J. GREER.
